UNITED STATES PATENT OFFICE.

EDWARD J. VON PEIN, OF DAYTON, OHIO, ASSIGNOR TO THE NATIONAL CASH REGISTER COMPANY, OF DAYTON, OHIO, A CORPORATION OF OHIO, (INCORPORATED IN 1906.)

PRINTING MECHANISM FOR CASH-REGISTERS.

1,230,241.

Specification of Letters Patent. Patented June 19, 1917.

Application filed July 18, 1914. Serial No. 851,762.

To all whom it may concern:

Be it known that I, EDWARD J. VON PEIN, a citizen of the United States, residing at Dayton, in the county of Montgomery and

5 State of Ohio, have invented certain new and useful Improvements in Printing Mechanism for Cash-Registers, of which I declare the following to be a full, clear, and exact description.

10 This invention relates to improvements in cash registers of the type having a plurality of totalizers in which a segregated analysis of transactions may be retained and printing mechanism comprising devices for printing certain reading matter and entering certain records of transactions on record material.

In the present instance the improvements are illustrated in connection with a register of the type shown and described in U. S.

20 Letters Patent 703,639 and 754,049, granted July 1, 1902 and March 8, 1904, respectively to Thos. Carroll, with improvements to the multiple totalizer mechanism shown and described in U. S. Letters Patent 1,062,767

25 issued May 27, 1913, to W. G. Chambers. This machine is, however, used only for the reason that it seems best adapted to illustrate the invention and it is not the desire to be limited to this particular embodiment of 30 the idea. The invention is capable of application in various forms to many other styles of cash registers and accounting machines.

One of the objects of the invention is to provide a machine which, in addition to performing the functions usually performed by cash registers, performs others which particularly adapt it to use in places where a number of checks are received and issued in the transaction of business. In addition to 40 having a plurality of totalizers for keeping a classified record of transactions, the machine shown herein is provided with devices for printing indorsements on the backs of checks, printing on the face of a check the 45 amount for which the check is drawn or indorsed, printing the name of the drawer of the check, the consecutive number and the date on the faces of checks issued, listing on a record strip retained in the machine items 50 of which a permanent record should be kept, and for listing a series of items on a record strip which can be torn off and used for checking off the items listed.

Another object is to provide means for

controlling a plurality of printing devices 55 such as just mentioned so that desired combinations of them may be rendered effective at an operation of the machine. In the present instance this controlling mechanism is operated by the totalizer selecting means 60 so that the proper combination of printing devices to take care of the different kinds of transactions is rendered effective as an incident to the selection of the totalizers. It will be apparent, however, when the invention is fully understood, that the controlling devices might readily be operated by means having no connection with totalizer selecting mechanism so that desired combinations of the printing devices could be rendered effective without reference to the nature or class of an item entered in a totalizer.

Another object is to provide driving connections whereby a printing device which may be adjusted to different positions, as, 75 for example, to accommodate different sizes of checks, can be so adjusted without at any time disabling said driving connections.

Another object is to provide an improved multiple record strip mechanism. In the 80 present embodiment the selection of a totalizer to receive an entry predetermines the record strip which will be brought to effective position to receive a printed record of the entry.

85 Still another object is to provide improved record strip feeding mechanism. As shown herein the feeding mechanism comprises an element having an invariable extent of movement and carrying a feeding pawl. 90 These parts are operated to feed the record strip during the forepart of the operation or before the impression is taken from the type. An adjustable stop is provided for disabling the pawl before the end of the driving 95 stroke of its carrying element. This brings the strip to a stop before the impression is taken, preventing the mutilation of the strip or the smearing of the amounts as they are printed. At the same time the fact that the 100 stop is adjustable provides a convenient means for regulating the width of the spaces between the printed items.

With these and incidental objects in view, the invention consists in certain novel features of construction and combinations of parts, the essential elements of which are set forth in appended claims, and a pre-

ferred form of embodiment of which is hereinafter described with reference to the drawings which accompany and form part of the specification.

5 Of said drawings:

Figure 1 is a reduced left elevation of the machine and shows the multiple totalizers, the totalizer selecting mechanism and certain features of the improvement.

10 Fig. 2 is an enlarged rear view of the printing mechanism and controlling devices associated therewith.

Fig. 3 is a right hand elevation of the machine on a reduced scale.

15 Figs. 3^a and 3^b combined constitute a right hand view of the printing mechanism, parts of the same being omitted for the sake of clearness.

Fig. 4 is a front elevation of the printing 20 mechanism and parts of the driving mechanism.

Fig. 5 is a top plan view on a reduced 25 scale of the sliding carriage and the record strip devices supported thereby on a reduced scale.

30 Figs. 6, 7 and 8 show in detail features of the printer controlling devices, particularly the relative positions of certain parts of said devices, and looking to the left end of the machine.

Fig. 9 is a detail of the record strip feeding mechanism.

Fig. 10 is a detail of the mechanism for moving the record strip carriage to place 35 the desired strip in effective position.

Fig. 11 is a detail of the cams for operating the record strip positioning devices and the strip device actuator.

40 Fig. 12 is a detail, partly in section, of feeding rollers comprised by one of the strip devices.

Fig. 13 is a detailed top plan of gearing for connecting and disconnecting one of the printing devices and the driving mechanism.

45 Figs. 14 and 15 are specimen checks showing the printing done thereon by the different printing devices, Fig. 14 representing a check issued by the user of the machine and Fig. 15 a check received and indorsed to the 50 bank of the user.

Fig. 16 is a reduced detail of the sliding strip frame.

The machine to which the invention is 55 shown applied has nine totalizers mounted in the usual rotatable reel with a manually adjustable lever and connections whereby the reel can be rotated to bring any desired totalizer into co-operative relation to a set of actuators common to all of the totalizers.

60 Five of these totalizers may be used for registering items such as the cash transactions handled by individuals, one may be used in the same way as an adding machine for totaling a series of items, another for 65 totaling the checks indorsed as for deposit

in bank, another for totaling the amounts for which checks are issued, and the remaining one for totaling the checks indorsed and cashed at the bank by the indorser.

The printing mechanism comprises a set 70 of type carriers set up under the control of a key board. Said mechanism also comprises five different printing devices. These are given names which are to a certain extent arbitrary, but which will be used as 75 consistently as possible throughout the description and claims to prevent any doubt as to just what is meant when one of the names is used. The five devices are as follows:

First, the devices provided for printing on the faces of inserted checks the amounts for which the checks are drawn or indorsed. These devices are usually spoken of herein as the "amount printing mechanism". The 80 second is the mechanism for printing on the faces of checks the name of the drawer, the date and the serial number of a check. This mechanism is usually termed herein the "check issuing mechanism". The third set 85 of devices is provided for printing indorsements on the backs of checks and is simply described as the "indorsing mechanism". The remaining two devices are the strip printing devices, either of which may be 90 brought to position to be operated to receive an impression from the common set of type carriers. One of these strip devices is arranged so that the strip is fed out of the machine as items are printed thereon so that 95 the strip may be torn off and used for checking off the items listed. This is described herein as the "checking strip mechanism". The other strip devices is arranged to wind the strip on a storage roll as the amounts 100 are printed on said strip. This strip is arranged to receive the entry of items of which a permanent printed record should be retained in the machine and has, therefore, been named the "permanent record strip 105 mechanism".

As before stated, the five devices are, in the present embodiment, rendered effective in various combinations to take care properly of items of the different classes by controlling devices operated as an incident to 110 adjustments of the totalizer selecting lever to position the desired totalizer. This controlling mechanism comprises a shaft rotated through suitable connections by operations of said lever and carrying stud bearing disks, one of these disks also carrying a cam, all arranged to operate connections which render their corresponding printing devices effective or ineffective depending 115 upon the position to which the shaft and disks have been rotated.

One of the printing devices, the indorsing device, is shown as being capable of adjustment to different positions. The purpose of 120

80

85

90

95

100

105

110

115

120

125

130

this is to accommodate checks of different lengths, that is to make it possible to position the indorsing device at the proper distance from the type carriers to permit printing both the indorsement on the back and the amount on the face of an inserted check at the same operation.

The type for printing the indorsement are carried by a rotatable cylinder. In order to give satisfactory results this cylinder must necessarily have a normal starting point and to insure its remaining in position the cylinder is locked against rotation during adjustment of the indorsing mechanism from one position to another. A driving gear having a fixed axis is provided for driving the cylinder. Gears intermediate the driving gear and the cylinder are pivoted to links arranged to permit the adjustment of the indorsing device from one position to another without at any time disabling the driving connection formed by said intermediate gearing.

The multiple record strip mechanism mentioned above comprises a sliding carriage to which are pivoted two rock frames for the record strips. A single actuating or operating element is provided for rocking whichever frame has been positioned in co-operative relationship to the operating element. When a frame is rocked a platen carried thereby presses its strip against the type carriers to take an impression from the type.

The devices for moving the sliding carriage, are, as before stated, controlled by the totalizer selecting mechanism. A pivoted element adjacent the carriage is operationally connected to the carriage so that if said element is rocked in either direction about its pivot the carriage will be moved. The pivoted element is rocked by a pitman having an invariable extent of movement at each operation, but so controlled by the controlling mechanism that it may be caused to engage said pivoted element at either side of its pivot, thereby rocking said element and sliding the carriage in either direction as desired to position the proper record strip to receive an impression of the item entered in the machine.

Driving mechanism.

In the accompanying drawings and the following description there is shown and described only those parts of the driving mechanism which have to do directly with the operation of the mechanism involved in the improvement. The rest of the driving mechanism is fully illustrated and described in the aforementioned patents and reference may be had to them for any desired information about the devices not shown and described herein.

Power is applied by means of a handle

19 (Fig. 3) of well known form or any other suitable form of driving means to a gear 20, shown partly broken away at the bottom of Fig. 4. This gear 20 is always meshed with a gear 21 rotatably mounted 70 on the printer frame 22. The gear 21 is indicated simply by its pitch line in Fig. 3. Meshing with the gear 21 is a gear 23 journaled on the shaft 24 and meshing with a gear 25 rotatably mounted on the printer 75 frame 22. The gear 25 meshes with a smaller gear 26 secured to one end of a sleeve 27 journaled on a short shaft supported by the printer frame 22 and the machine frame 32, said sleeve carrying at its 80 other end a gear 28 of the same diameter as the gear 26 and meshing with a large intermediate gear 29, (Fig. 4.) The gear 29 is rotatably mounted on a stub shaft in the machine frame 32. Spacing collars 31 hold 85 the gears 26, 28 and 29 at the proper distance from the machine frame. Meshing with the large intermediate gear 29 is a gear 33 fast to a shaft 34 (Figs. 2 and 4) and in turn meshing with a gear 35 (Figs. 2 and 3) 90 secured to a shaft 36. The shafts 34 and 36 extend across the machine and are the main driving shafts for the mechanism. A gear 37 of the same diameter as the gear 35 is also secured to the shaft 36 and drives 95 a gear 38 fastened to a shaft 39 journaled in the printer frame 22 and machine frame 32. The gearing described is so proportioned that for each two turns of the gear 20, the shafts 34, 36 and 39 each make a 100 complete rotation. As will appear more fully later, all but one of the various printing mechanisms are operated from these three shafts.

Totalizer selecting mechanism.

The multiple totalizer mechanism and the totalizer selecting devices are shown in Fig. 1. As stated before, the machine has nine totalizers. These are supported by a reel 40 rotatably mounted on a shaft 41 carried by a sliding frame 42. A lever 43 attached to a shaft 44 journaled in the adjacent machine frame 45 carries a rack 46 meshing with the teeth 47 of a segment gear journaled on a short shaft 48. Rigid with the segment gear 47, is a second segment gear 49 meshing with a pinion 51, fastened to and concentric with the totalizer reel 41. By tracing the movement through the mechanism just described, it will be seen that as the lever 43 is rotated about its pivot 44 the reel 40 is turned, and by this means any desired one of the totalizers mounted on said reel, may be brought into co-operative relationship 110 with a set of actuating rack segments, indicated by the pitch line 52, common to all of the totalizers. The actuators are operated by differential mechanism controlled 115 by banks of keys 53. The differential mecha- 120 125 130

nism is not shown and described in this application, but is fully shown and described in each of the patents mentioned above.

- 5 Just before the actuators are operated by the differential mechanism, the selected totalizer is carried up into engagement with said actuators by a cam 54 acting against a roller 55 attached to the side of an element 10 operatively connected to the sliding frame 43. After the actuators have entered the items in the totalizer, the sliding frame 42 is lowered by a cam 56 acting against a roller 57 attached to the sliding frame 42. 15 The cams 54 and 56 are both fastened to the main driving shaft 34, which shaft it will be remembered receives one complete rotation at each operation of the machine. The mechanism for moving the totalizers in 20 and out of engagement with the actuators is more fully described and shown in the hereinbefore mentioned patents.

Printer controlling mechanism.

- 25 Attached to the shaft 44, to which the lever 43 is fastened, is a large gear segment 61 meshing with a gear 62 attached to a shaft 63 extending across the machine. At its opposite end, that is, the end nearest the 30 printer, the shaft 63 carries fastened thereto three disks 64, 65 and 66 (Figs. 2, 3^b, 6, 7 and 8). One of these disks has a cam formed on its periphery to control one of the five printing devices mentioned above, 35 while each of the disks carries a plurality of studs. Coöperating with the studs on the disks 64, 65 and 66 respectively are three armed levers 71, 72 and 73. These levers are pivoted on a rod 74 (Fig. 3^b) supported 40 by the printer frame 22 and the machine frame 32, and are held against lateral displacement by collars 75 (Fig. 2) on the rod. The studs are arranged on the disks 64, 65 and 66 in two series, one series on each side 45 of the disks, and the two upwardly extending arms of the three armed levers, are staggered as shown in Fig. 2, so that each arm coöperates only with the studs on one side of a disk. The third arms of the levers 50 operate connections controlling four of the five printing devices. The fifth printing device is controlled by a cam on the disk 66. The arrangement of the studs on the disk, and the manner in which they operate the 55 three armed levers and the devices connected to said levers, will be described in detail later on. It is sufficient to state here that the studs are placed on the disks 64, 65 and 66 with reference to the positions of the 60 totalizer selecting lever 43, so that when said lever is set to position a desired totalizer opposite the actuators, the studs in the disks will have adjusted the three armed levers and their connections to render effective the proper combination of the four 65

printing devices to take care of an entry of the class assigned to that particular totalizer.

Printing mechanism.

The printing mechanism comprises a set of type carriers 81 (Figs. 3, 3^a and 4). These carriers are equipped with two sets of type on their peripheries, the like type being diametrically opposite so that two impressions may be taken at the same time from the opposite sides of said carriers. One of the type carriers is operated by mechanism directly connected to the lever 43, while the others are operated by the differential mechanism controlled by the banks of keys 53. Three of the five printing devices take their impressions from this set of the type carriers. 70 75 80 85

The ink for the type carriers is supplied by pads 82 and 83 (Figs. 3 and 3^a) the former inking the upper set of type and the latter the lower type. These pads are supported by plates 84 and 85 extending across the carriers, and pivoted so as to have a limited movement on rods 86 and 87 carried by the oppositely extending arms of a pair of elements 91, pivoted as at 92. Only one of the elements 91, the outer or right hand one, is shown in the drawings. The other, 90 that is, the one nearest the machine proper, is substantially the same as the one shown, but has rigid therewith a partial gear 93. Meshing with the teeth of the gear 93 are the teeth of a rack 94. This rack 94 is 100 guided at its lower end by a pin 95 extending through a slot in said rack, and at its upper end by a hook over the shaft 34. An anti-friction roller 96 carried by the rack 94 projects laterally into a cam groove 97, 105 formed in the side of a disk 98 rigidly attached to the shaft 34. See Figs. 2, 3^a and 4. It will be recalled that the shaft 34 is one of the main driving shafts, and receives a complete rotation at each operation of the 110 machine. The configuration of the cam groove 97 is such that the rack 94 is raised gradually during the early part of the operation, and rocks the elements 91 about their pivots 92 until by the time the type 115 carriers are fully positioned by the differential mechanism, the pad 82 is resting above and the pad 83 below the type carriers 81. Both pads are then pressed against the type, (by means which will be described 120 fully later) after which the rack 94 is restored to normal position and the ink pads swung back to the positions in which they are shown in Figs. 3 and 3^a. 125 130

Amount printing device.

The five printing devices hereinbefore mentioned will next be described. First, the device which is herein called the amount printing device. This is the mechanism for 130

printing the amount of a registration on the face of a check or similar paper inserted in the printer and comprises a platen 101 (Fig. 3^a) adjustably mounted in a bar 102 having upwardly extending ears 103 pivoted at 104 to arms 105 secured to a rock shaft 106. One end of the shaft 106 is journaled in a plate 107 secured by screws 108 to studs 109 (Fig. 4) attached to the printer frame 22. The other end of the shaft is journaled in and extends through said frame 22. To the end of the shaft last mentioned is secured an arm 111 carrying a stud 112. Coöperating with this stud is a notch 15 in the lower end of a pitman 113 slotted at its upper end to straddle the shaft 34, and carrying an anti-friction roller 114 projecting into a cam groove 115 formed in the side of a disk 116 (Figs. 2 and 4) secured 20 to the main driving shaft 34. The cam groove 115 is so shaped that the pitman 113 is first thrust downward a certain distance, and then partially returned toward normal. It is then thrust downward a greater distance, after which it is restored to its original starting point. The first movement of the pitman, through the mechanism described, forces the platen 101 down far enough to press against the type carriers 30 the ink pad 82, which has by this time been brought between the platen and the type carriers. The partial return toward normal of the pitman 113 withdraws the platen far enough to free the ink pad and permit 35 its withdrawal, after which the second thrust of the pitman presses the inserted check against the type carriers 81 to take an impression from the type.

A plate 98, supported by the two lower ones of the studs 109 to which plate 107 is attached, has an opening through which the platen and its carrying bar 102 operate. Said opening is so arranged that the plate acts as a guide for the platen.

45 In order to hold the inserted check stationary while an impression is being taken by means of the platen 101, there is provided a gripper 124 (Fig. 3^a). This gripper is pivoted on one of the plate supporting studs 109 and rests against the top of a screw 110 set in the platen carrying bar 102. When the platen is lowered, as above described, a spring (not shown) rocks the gripper 124 about its pivot until the rear 50 end of the gripper contacts the inserted paper and holds it against the top of the supporting table 125. This movement is permitted by a slot (not shown) in the plate 98. When the platen is restored to 55 normal position, the gripper 124 is withdrawn and the paper freed so that it can be removed.

60 The pitman 113 is normally held forward with the notch in its lower end in engagement with the stud 112 by a spring 117 hav-

ing one end fastened to the pitman and the other to a stud in the printer frame 22. However, it is necessary to disable this amount printing device when items of certain classes are entered. This is accomplished by providing mechanism whereby, when the totalizer selecting lever is adjusted to certain positions, the pitman 113 is automatically disconnected from the stud 112.

70 A lever 118 (Figs. 3^a, 3^b and 6) pivoted on a stud 119 on the printer frame 22 carries at its upper end a stud 121 extending through a slot 122 in the pitman 113. The lower end of the lever 118 rests against the periphery of the disk 66. A cam 123 on the periphery of said disk will, when the totalizer selecting lever is at certain positions, engage the lever 118 and rock it clockwise, Figs. 3^a and 3^b. This movement of the lever 118 will, through the slot and pin connection between the lever and the pitman 113 swing the pitman counter clockwise about the shaft 34 and against the tension of the spring 117 far enough to disengage the hook on the lower end of the pitman from the stud 112, and hold it disengaged as long as the lever 43 remains in one of the positions at which the cam 123 contacts the lower end of the lever 118. 80 Then when the pitman 113 is given its downward thrust, the movement will be an idle one, and the platen will not be moved. 85

90 It is apparent that unless some means is provided to hold the platen 101 in normal position when the pitman 113 is disconnected from the stud 112, said platen will be thrown down by the spring which operates the gripper arm 124. Then when the pitman 113 is moved by the spring 117 to 95 reengage the hook on the pitman with the stud 112, said stud will be out of normal position and the hook will miss it. In order to overcome this, there is provided a spring 126, secured at one end to the stud 112, and at the other to a stud 127 in the printer frame 22. This spring 126 is superior enough in strength to the spring for operating the gripper arm 124 to hold the platen mechanism in normal position when the 100 pitman 113 is disabled.

Check issuing mechanism.

105 The second of the printing devices, as listed above, is the one which is called herein the "check issuing mechanism". This mechanism prints on the face of the check the name of the drawer, the consecutive number of the check, and the date on which it was issued. See Fig. 14. The name of the 110 drawer is printed from a type carrier in the form of an electro attached to the periphery of a cylinder 131 (Fig. 3^a) carrying in its interior the date and consecutive number printing mechanism. This mechanism is 115 120 125 130

well known in the art and needs no explanation. The cylinder 131 is rigidly attached to the shaft 24 (Fig. 4) upon which the driving gear 23 described above is rotatably mounted. Rigid with the gear 23 is a gear 132 (Figs. 4 and 13) and secured to the shaft 24 is a gear 133. A broad toothed pinion 134 is arranged to be thrown in and out of engagement with the gears 132 and 133, thereby forming a driving connection between the driving mechanism proper and the cylinder 131. This broad toothed pinion is rotatably mounted at the upper end of an arm 136 secured to a short shaft 137 journaled in the printer frame to which shaft is also attached an arm 138. Pivoted to the lower end of arm 138 is one end of a link 141 (Figs. 3^b and 6) pivoted at its other end to the downwardly extending arm 20 of the three armed lever 72. This lever is rocked in one direction or the other by the studs on the disk 65. These studs are so positioned on the disk with reference to the lever 43 that at certain positions of said lever the link 141 is thrown forward and the broad toothed pinion 134 swung into mesh with the gears 132 and 133. Then when the driving mechanism is operated, the shaft 124 and the cylinder 131 carried by said shaft are given one complete rotation, during which the type carried by the cylinder are inked and consecutive number and name of the drawer are printed on the check. The ink is supplied by an inking roller 143 with which the type come in contact as the cylinder 131 is turned.

As shown at 139, Fig. 14, on a check issuing operation the amount for which the check is drawn is printed below the matter printed by the cylinder 131. This amount is printed by means of the platen 101 from the type carriers 81. In order to bring the amount in proper relation to the other information printed on the check, the check must be fed over the cylinder 131 to receive an impression from its printing devices and carried rearward far enough to bring the proper point on the check under the platen 101. This is accomplished in the usual way by flanges 144 (Figs. 3^a and 4) carried by the cylinder and coöperating with a roller 145 rotatably mounted above the cylinder 131 and at the proper distance therefrom to be engaged by said flanges as the cylinder is rotated.

As shown in Fig. 3^a, the feeding flange 144 is cut away so as not to grip the check against the roller 145 until shortly after the operation of the machine is commenced. 60 The consecutive numbering wheels, the date and the electrotype are positioned on the cylinder 131 to print as soon as possible after the flange 144 begins to feed the check, and said flange is long enough in this in-

stance to feed the check through to bring 65 the proper point on the same under the platen 101. The platen is then operated as above described to take an impression of the amount for which the check is drawn as set up on the type carriers 81. 70

Indorsing mechanism.

The third of the five printing devices is the indorsing mechanism. This mechanism is arranged to print the usual indorsement 75 on the back of inserted checks, as shown in Fig. 15, and is similar in its operation to the check issuing mechanism described in the foregoing. That is to say, it prints all of the indorsement except the date from an 80 electrotype attached to a rotatable cylinder 151 (Fig. 3^b) equipped with flanges 154 arranged to feed the check forward toward the type carriers 81 as the indorsement is 85 printed. The date of the indorsement is 90 printed from the usual date wheels carried in the interior of the cylinder. In addition to the cylinder 151 the indorsing mechanism comprises an inking roller 152 for inking the electrotype, and an impression roller 153 95 coöperating with the electrotype and feeding flanges 154 on the cylinder to print the indorsement and feed the check. The cylinder 151, the inking roller 152, and the impression roller 153 are rotatably mounted 100 on shafts journaled in a frame 155 arranged to slide back and forth along rails 156 and 157. The purpose of this sliding movement, it will be recalled, is to permit positioning the indorsing cylinder 151 at different distances from the type carriers 81 so that the indorsement and the amount for which the indorsement is made can be printed at one 105 operation on checks of different lengths. The lower rail 157 is rigidly attached to 110 printer frame 22, but the upper rail 156 has slots through which pass screws 158 attaching said rail to the printer frame 22. This slotted connection is provided to permit a certain amount of adjustment of the rail 115 156. Adjusting screws 161 set in the upper edge of the rail coöperate with lugs 162 on the printer frame 22 and by turning these screws in either direction the distance between the rails 156 and 157 may be regulated. Both of the rails and the frame 155 120 are equipped with ball races 163 in which are placed ball bearings 164 to make the adjustment of the frame along the rails as nearly frictionless as possible.

Latch mechanism is provided for holding the frame 155 in any of the positions to which it may be adjusted. This latch mechanism comprises a rack 165, Figs. 2, 3 and 3^b, supported by studs 166 on the printer frame 22. Coöperating with the rack 165 is a latch plate 167 slotted as at 168 and 169 to straddle respectively a rock shaft 171 125

5 journaled in the sliding frame 155 and the shaft 172 to which the cylinder 151 is fastened. Attached to the rock shaft 171 is an arm 175 carrying a stud 176 extending through a short slot 177 in the latch plate 167. One end of the rock shaft 171 is provided with a handle 178 by means of which the shaft 171 may be rocked against the tension of a spring 179 (Fig. 2) surrounding 10 said shaft, thereby causing the arm 175 to slide the plate 167 downward far enough to disengage the nose 181 of the plate from the rack 165. While the plate is held in this lowered position by means of the handle, the frame 155 may be adjusted to any position desired and the handle 178 released allowing the spring 179 to restore the rock shaft to its original position and engage the nose 181 on the latch plate 167 15 with the proper notch in the rack 165.

20 In order to prevent the cylinder 151 from rotating during this adjustment from one position to another, the latch plate 167 is provided with a stud 183 which when said plate is drawn down by operation of the handle 178 engages a notch 184 in the edge of a disk 185 rigid with the cylinder 151 and prevents the cylinder from rotating as long as the handle 178 is depressed.

25 The cylinder 151 is driven from the driving shaft 36. Rigidly attached to said shaft is a gear 186, Fig. 2. Adjacent to the gear 186 is a gear 187 secured to a sleeve 188 loose on the shaft 36 and having attached 30 to its other end a gear 189. A broad toothed pinion 191 is provided for connecting gears 186 and 187 when the indorsing cylinder 151 is to be driven. This broad toothed pinion is rotatably mounted on a stud on 35 the upper end of an arm 192 attached to a shaft 193 journaled in the printer frame 22, and having attached to its opposite end a rearwardly extending arm 194. Spacing collars 195 on the shaft 193 hold said shaft 40 and the parts attached thereto in their correct positions. Pivoted to the rearwardly extending arm 194 is one end of a link 196 pivotally connected at its lower end to the arm which extends rearwardly, of the three 45 armed lever 71. This lever cooperates with the stud bearing disk 64 on which the studs are so arranged that at certain positions of the totalizer selecting lever 43 the lever 71 is rocked to lower the link 196 and swing 50 the broad toothed pinion 191 up out of the position in which it is shown in Figs. 2 and 3^b, thereby disabling the driving connection between gears 186 and 187.

55 In order to prevent the gears 186 and 187 from getting out of alignment when the broad toothed pinion is disengaged the arm 192 has a downwardly extending portion 198 provided with a tooth which is swung into engagement with the gear 187 as the

broad toothed pinion 191 is disengaged 65 from the gears. At the same time the pinion is carried into engagement with a pin 200 on the frame 22 to prevent rotation of the pinion.

70 Power is transmitted from the gear 189 through intermediate gears to a gear 201, Figs. 2 and 3^b, rigid on the shaft 172 to which the cylinder 151 is attached. The intermediate gears are designated by the numerals 202 and 203, Figs. 2 and 3^b. In 75 order to permit the adjustment of the frame 155 from one position to another without disabling the driving connection between the gears 189 and 201, a series of links 204, 205 and 206 are provided, the series being 80 pivoted at one end on the shaft 36 and at the other on the shaft 172 carrying the cylinder 151. The links 204 and 206 have fastened thereto studs 207 and 208 respectively, 85 forming supports for the third link 205 and projecting far enough to form axes for the intermediate gears 202 and 203. As the frame 155 is moved forward, from the position in which it is shown in Fig. 3^b, to bring the cylinder 151 nearer the type carriers 81, the links 204, 205 and 206 are 90 caused to buckle up and the gears 202 and 203 are rotated slightly with reference to each other and to the gears 189 and 201, but all of the gears remain in mesh. This permits adjustment of the frame 155 and the parts carried thereby without at any time disabling the driving connection between the driving gear 189 and the driving gear 201 rigid with the cylinder. 95

100 The sliding adjustment of the frame 155 makes desirable some form of support for the inserted check other than the usual table. For this reason there is provided a belt 211 supported by four studs, as shown in Figs. 2, 3^a and 3^b, and passing through slots in a plate 213 partially surrounding the impression roller 153 and arranged to prevent the belt from contacting said roller. 105 A spring 214 connects the ends of the belt 110 and serves to keep it taut.

Checking and permanent record strip devices.

115 The remaining two of the five printing devices, the checking strip and the permanent record strip devices, will next be described. As before stated, these devices are carried on rock frames pivoted to a sliding frame arranged to be moved back and forth 120 to bring either of the frames to effective printing position. An invariably moved operating element then rocks the positioned frame, causing a platen carried by the frame to press the paper strip against the type 125 carriers.

The sliding frame is designated in the various figures by the numeral 215. As best

shown in Figs. 4 and 16 it is mounted in slides 216 carried by the printer frame 22. Rigid on the frame 215 is an arm 217, Figs. 5, 6, 10 and 16 carrying a stud 218 engaging a slot in the upper end of an arm 219 pivoted as at 221 to the printer frame 22. It is apparent that by rocking this arm about its pivot the frame 215 may be slid in either direction.

10 The means for rocking the arm 219 comprises studs 222 carried by oppositely extending portions of the arm 219 and projecting through curved openings 223 in the printer frame 22, and a pitman 224. Said pitman is slidably supported at its upper end by the shaft 36 and is provided with an anti-friction roller 225, Fig. 11, projecting into a cam groove 226 in a disk 227 attached to a shaft 36. It will be remembered 15 that the shaft 36 is one of the main driving shafts and is given a complete rotation at each operation of the driving mechanism. The cam groove 226 is so formed that during the rotation of the shaft the pitman 224 is invariably raised and then lowered at each 20 operation. At its lower end said pitman has oppositely extending projections 231 and 232 to coöperate with the studs 222. The pitman 224 can be swung slightly about 25 the shaft 36 so as to bring either the projection 231 or the projection 232 under the corresponding stud 222. Then when the pitman is raised, if the stud under which 30 one of the projections on the pitman has been moved is in the lowered position the arm 219 will be rocked about its pivot and slide the frame in the corresponding direction. This mechanism it will be seen permits moving the frame 215 to the desired 35 position by an operation of the driving mechanism and leaving it in that position during successive operations or until it is desired to position the other record strip. In other words the sliding frame 215 is not necessarily moved at each operation of the 40 operating mechanism.

The pitman 224 is slotted at its lower end to receive a stud 233 carried by the downwardly extending arm of the three armed lever 73. The studs in the disk 66 coöperating with said lever 73 are so arranged 45 that as the totalizer selecting lever is adjusted from one position to another the arm 73 may be rocked and, through the stud 233, the pitman 224 swung to position one or the other of its extensions under one of the studs 222. Then when the pitman 224 is raised as above described, the arm 219 may be rocked and the sliding frame moved to its desired 50 position.

The checking strip mechanism is carried by the rock frame 234, Figs. 3^a, 4, 5, 9 and 16, pivoted on a stud 236 on the sliding frame 215. A spring 237 on said stud is ar-

ranged to hold the rock frame in normal 65 position against a stop 240, Fig. 5, on the sliding frame. The checking strip 238 is drawn from a supply roll 239 supported by a stud 241 on the rock frame 234 and passes over the top of a platen 242, then down between said platen and a feeding roller 243 and out over the guide 244. A serrated knife 245 is provided so that after a series of items has been listed on the strip the strip can be torn off and used for checking off the 70 items listed. The feeding roller 243, as best shown in Fig. 9 has rigid therewith a ratchet wheel 246. Coöperating with said ratchet wheel is a spring pressed pawl 247 pivoted to a plate 248 rotatably mounted 80 on a shaft 249 supporting the feeding roller 243. Pivoted to an ear 251 on the plate 248 is a link 252 loosely connected at its lower end to an arm 253 fastened on a rock shaft 254, Figs. 4, 5 and 9, journaled in the sliding frame 215. The shaft 254 extends through the outer casing of the printing mechanism and has attached to its exposed end a handle 255. A spring 256 holds the parts in the normal position in which they 85 are shown in the various figures. When it is desired to feed the checking strip 238 so as to bring it out far enough to permit tearing off the amounts printed thereon the handle 255 is drawn forward and released 90 the number of times necessary to feed the printed items past the knife 245.

In operations of the machine with the checking strip in effective position the rock frame 234 is rocked anti-clockwise Figs. 3, 100 8, and 9, so that the platen 242 presses the paper against the type carriers 81. During this rocking movement of the frame the link 252 is, of course, held against movement by the shaft 254 on which it is pivoted, causing 105 the plate 248 to be swung about the shaft 249. The result is that the rocking movement of the frame 234 causes the pawl 247 to rotate the feeding roller 243. A spring operated retaining pawl 261 carried by the 110 rock frame 234 coöperates with the ratchet wheel 246 to hold the feeding roller 243 in the position to which it is turned by the operating pawl.

To prevent movement of the paper while 115 an impression is being taken, there is provided an adjustable stop 262 (Fig. 9) carried by the rock frame 234 against which the tail 263 of the pawl 247 strikes near the end of its feeding movement. This 120 results in the nose of the feeding pawl being disengaged from the ratchet 246 before the plate 248 carrying the pawl has completed its stroke. It is apparent that this will prevent further movement of the paper 125 and that by adjusting the stop 262 the time at which the pawl 247 will be disengaged from its ratchet may be controlled, thereby

affording a convenient means whereby the width of the spaces between the printed items may be regulated.

In order to accommodate different thicknesses of checking strip an eccentric adjustment is provided to permit regulating the distance between the platen 242 and the feeding roller 243. This eccentric adjustment is best shown in Fig. 12. The shaft 249 supporting the roller 243 carries an eccentric sleeve 263 about which the roller 243 rotates. The sleeve 263 is threaded at its outer end to receive a thumb nut 264 provided to clamp a plate 265 against the end 15 of said sleeve. As shown in Fig. 3^a the plate 265 is hooked at its rear end to engage a shaft 259 upon which the platen 242 is mounted. Said shaft is arranged to receive a thumb screw 260 so that the hooked end 20 of the plate 265 can be clamped against a shoulder 266 on said shaft. In order to change the distance between the platen 242 and the roller 243 it is necessary to remove the thumb nut 264 and loosen the thumb 25 screw 260. The hooked end of the plate 265 can then be raised out of engagement with the shaft 259 and the eccentric sleeve 263 rotated the proper distance, after which the thumb nut 264 is again tightened to clamp 30 the plate 265 and eccentric sleeve 263 together. The plate 265 is then swung back to engage its hook with the shaft 259 and the thumb screw 260 tightened to hold it in position.

In addition to affording a means whereby pressure between the platen and the feeding roller may be regulated, the eccentric construction described affords a convenient means for separating the platen and roller 40 when threading the checking strip through the printer, as to separate them it is only necessary to loosen the thumb nut 260 so that the plate 265 may be disengaged from the shaft 259 and swung upward. This 45 causes the eccentric sleeve clamped to the plate 265 to move the feeding roller 242 away from the platen 243 so that the paper may be passed readily between them.

The permanent record strip mechanism is 50 similar in construction and operation to the checking strip mechanism just described. It comprises a rock frame 271, Figs. 3^a, 3^b and 5, similar to the rock frame 215 for the checking strip and has the same kind of 55 paper feeding pawl operating and controlling mechanism. The shape of some of the parts and their relative position are a little different, due mainly to the fact that the permanent record strip is to the rear instead of in front of the type carriers 81 but the only substantial difference is that in the permanent record strip device the record strip 272 is wound on a storage roll 273 after it is printed by means of a platen

274 instead of being fed out of the machine 65 as was seen to be the case with the checking strip. Owing to this similarity between the two strip devices it is thought that no further description of the permanent record strip mechanism need be given here. 70

Platen operating mechanism.

As already stated, after the sliding frame 215 is moved to position the desired strip the rock frame carrying said strip is rocked 75 by an element having an invariable movement at each operation of the machine. This invariably moved element is in the form of a lever, Figs. 2, 3^a, 3^b and 5, the general shape of which can be best seen in the figure last 80 mentioned. This lever is pivoted on a stud 281 on the printer frame 22 and has an arm 282 extending toward the front of the machine with a portion 283 formed at right angles to the length of the lever. Extending 85 through said portion 283 are set screws 284. These set screws are to raise whichever one of the platens 242 or 274 has been brought to operative position by adjustment of the totalizer selecting lever 43 and subsequent 90 operation of the machine. By adjusting the set screws in either direction the impression taken by the platens may be regulated.

To a rearwardly extending arm 285 of the lever is pivoted one end of a pitman 95 286, Figs. 2, 3^b and 11, slidably supported at its upper end by the shaft 39 and carrying an anti-friction roller 287 projecting into a cam groove 288, Fig. 11, in the disk 289 secured to the shaft 39. This shaft, as 100 before explained, makes a complete rotation at each operation of the machine. The cam groove 288 is so shaped that near the end of an operation the pitman 286 is thrust downward a certain distance and then 105 partially returned toward normal, after which it is thrust downward a greater distance and is then returned to normal. This rocks the lever 280 clockwise, Figs. 3^a and 3^b, lifting the positioned platen twice, first 110 to press the ink pad against the type carriers, after which the pad is withdrawn and then to take an impression from the type carriers. This incidentally rocks the frame carrying the platen so as to operate 115 the paper feeding devices.

Operation of the printer controlling mechanism.

The five printing devices have now been 120 described in detail, also the mechanism by which they are operated and, in a general way, the manner in which each is separately controlled by means of the totalizer selecting lever 43. A detailed description will 125 now be given of the operation of the controlling mechanism as a whole to render effective the various combinations of the

printing devices. Before doing this, however, it is necessary to explain more fully than was done in the general statement the functions of each of the totalizers shown 5 in Fig. 1.

As stated in the general description of the machine five of the nine totalizers shown 10 may be used to record ordinary transactions such as cash sales handled by different clerks. These five totalizers are designated 15 in Fig. 1 by the numerals 291 to 295 inclusive. The sixth totalizer 296 is in this particular machine intended to be used simply as a convenience in totalizing any series 20 of items, that is, with this totalizer in position the register may be used in the same way as the ordinary adding machine. The 25 seventh totalizer 297 is to retain the total of checks indorsed as for deposit in the bank. The eighth, designated by the numeral 298, is to totalize the amounts for which checks are issued, and the remaining 30 totalizer 299 is to totalize the amounts of checks drawn and cashed at the bank by the drawer. The mechanism whereby the 35 totalizers may be selectively positioned with reference to the actuators by adjusting the lever 43 has already been described, also the connection whereby the adjustment of 40 said lever positions the printer controlling disks 64, 65 and 66.

In Fig. 1 the totalizer selecting lever is 45 shown in its lowest position with the totalizer 299 opposite the actuators 52. The 50 positions in which the stud bearing disks 64, 65 and 66 rest at this position of the lever 43 are shown in Figs. 6, 7 and 8. When the lever 43 was adjusted to its lowest 55 position a stud 301 on the disk 64 was carried into contact with the forward upwardly extending arm of the three armed lever 71 rocking the lever counter-clockwise, Figs. 3^b, 6 and 8 and, by means of the link 196, swinging the broad toothed pinion 191 into 60 engagement with the gears 186 and 187, thereby connecting the indorsing mechanism to the driving mechanism. At the same time a stud 302 on the disk 65 was brought into contact with the forward 65 upwardly extending arm of the three armed lever 72 rocking this lever also in a counter-clockwise direction. This, through the link 141, swings the broad toothed pinion 184 out of engagement with the gears 132 and 133 to disconnect the check issuing mechanism from the driving mechanism. The third stud bearing disk 66, it will be recalled, controls the positioning of the sliding record strip carriage 215 70 and also by means of the cam 123 formed on its periphery controls the operation of the amount printing platen 101. At the same instant that the studs 301 and 302 become effective, as just described, a stud 303 on 75 the disk 66 came into engagement with

the rear upwardly extending arm of the three armed lever 73 and rocked said lever clockwise Figs. 3^b and 6 this swinging the lower end of the pitman 224 forward to position its extension 232 under the forward stud 222 carried by the rocking frame 219. Then at the subsequent operation of the machine the pitman will, if the preceding entry was made on the permanent record strip, rock the arm 219 clockwise, Figs. 3^b 80 and 10, about its pivot 221 and slide the carriage 215 rearwardly to bring the checking strip 238 to effective position. At this position of the disk the cam 123 is out of contact with the lever 118 so that said lever is not operated to disconnect the pitman 113 from the device for operating the amount printing platen 101. It will be seen, therefore, that when the lever 43 is set to position the totalizer 299 opposite the actuators 85 85 the indorsing and amount printing devices are effective to print on the back and front respectively of inserted checks and a record of the amount entered in the totalizer and printed on the check is made on the checking strip 238. As previously stated the totalizer 299 retains the totals of all checks indorsed and cashed at the bank by the indorser. The sample check shown in Fig. 15 was indorsed and the amount printed as shown at 199 with the lever 43 at the position mentioned, that is, at its lowest position.

When the totalizer selecting lever 43 is at 90 its next to the lowest position the totalizer 298 is opposite the actuators 52. This totalizer is to retain the total of the checks issued. If the lever 43 is adjusted to this 95 position the studs 304 and 305 are carried into contact with the rear arms of the three armed levers 71 and 72 respectively, rocking said arms clockwise Figs. 3^b and 6. This causes the broad toothed pinion 191 operated by the lever 71 to be swung out of engagement with the gears 186 and 187 thereby 100 disconnecting the indorsing mechanism from the driving mechanism, while the broad toothed pinion 134 operated by the lever 72 is swung into engagement with the gears 132 and 133 thereby connecting the check issuing 105 cylinders 131 to the driving mechanism. At the same time a stud 306 on the disk 66 will be carried into contact with the forward arm of the three armed lever 73, swinging the lower end of the pitman 224 toward 110 the rear to bring its extension 231 under the rear stud 222 on the rocking arm 219. Subsequent operation of the machine will then cause said arm 219 to be rocked counter-clockwise Figs. 3^b and 10, moving the sliding frame 215 forward and placing the permanent record strip 272 in position to receive entries from the type-carriers. The cam 123 on the disk 66 is at this second position of the lever 43 still out of engagement 115 120 125 130

with the lever 118 so that the pitman for the amount printing platen 101 will not be disconnected. It is clear therefore that at this position of the lever 43 the check issuing cylinder 131 and the amount printing platen 101 are effective to print on the inserted check the consecutive number, the date, the name of the drawer and the amount for which the check is issued, and said amount is also printed on the permanent record strip. A specimen check printed with the lever 43 at this position is shown in Fig. 14.

When the lever 43 is adjusted to the third from the bottom position the totalizer 297 is brought into coöperative relation with the actuators. This totalizer is to retain the total of all checks indorsed as for deposit in bank. When the lever 43 is adjusted to this position the studs 307, 308 and 309 carried by the disks 64, 65 and 66 respectively are brought into engagement with the forward arms of the levers 71, 72 and 73 rocking all of said levers anti-clockwise, if they have not already been rocked in that direction. The lever 71 will then hold the broad toothed pinion 191 in engagement with the gears 186 and 187 thereby rendering the indorsing mechanism effective, the lever 72 will hold the broad toothed pinion out of engagement with the gears 132 and 133 thereby disconnecting the check issuing cylinder 131 from the driving mechanism, while the lever 73 will hold the pitman 224 rearward to position the permanent record strip platen opposite the type-carriers. The movement of the disk 66 to this position carried the cam 123 on said disk against the lower end of the lever 118 operating the lever to disconnect the driving pitman 113 from the device for operating the amount printing platen 101. Briefly stated, therefore, when the lever 43 is adjusted to position the totalizer 297 opposite the actuators 52 and the machine operated an indorsement will be printed on the back of an inserted check and the amount for which it is indorsed will be printed on the permanent record strip.

As above stated the totalizer 296 is designed to be used simply as a convenience in totaling any series of items. When the lever 43 is adjusted to position this totalizer at the actuators the amount printing device, the check issuing device, and the indorsing device are disabled and the checking strip is moved to effective position. Moving the checking strip to effective position, of course, renders the permanent record strip devices ineffective. By this arrangement amounts entered in the totalizer 296 are listed on the checking strip 238 and, as previously explained, this strip may be fed out of the machine and torn off to be used in checking the items entered. At this position of the lever 43 a stud 311 on the disk 64 rests against the rear arm of the lever 71 holding

the broad toothed pinion 191 out of mesh, a stud 312 on the disk 65 rests against the forward arm of the lever 72 holding the broad toothed pinion 134 out of mesh and the cam 123 on the disk 66 has operated the lever 118 and is holding it in the operated position, thereby disabling the pitman 113 and preventing operation of the amount printing platen 101. The stud 313 on the disk 66 is at the same time resting against the rear arm of the three armed lever 73, holding the lower end of the pitman 224 forward so that when said pitman is reciprocated it will move the sliding frame 215 to position the checking strip 238 under the type-carriers 81.

When any one of the five clerks' totalizers 291 to 295 inclusive is in position to receive entries from the actuators, the entries are listed on the permanent record strip 272. The amount printing platen 101 is also operated to print the amount of each transaction on the face of a sales slip filled out by the clerk and inserted under the type-carriers. When the clerk's totalizer 295 is positioned opposite the actuators a stud 314 on the disk 64 will be in contact with the rear arm of the three armed lever 71, holding the broad toothed pinion 191 out of engagement and disabling the indorsing device, a stud 315 on the disk 65 will be in contact with the forward arm of the lever 72 holding the broad toothed pinion 134 disengaged, disabling the check issuing cylinder 131, while a stud 316 on the disk 66 will be in contact with the forward arm of the lever 73, thereby holding the lower end of the pitman 224 toward the rear, that is, in position to bring the permanent record strip 272 under the type-carriers 81. At this position the cam 123 has passed out of engagement with the lever 118 and the pitman 113 is effective to operate the platen 101. For the sake of clearness the studs which would be effective when the clerks' totalizers 291 to 294 inclusive are placed at the actuators have been omitted. It is apparent, however, that they would be so placed on their disks as to control the same combination of printing devices as the studs 314, 315 and 316 just mentioned.

In describing the construction of the mechanism comprised by the improvement it has been necessary incidentally to give a thorough explanation of the operation of the different devices. It is thought, therefore, that the usual summary of the operation may in this case be omitted.

While the form of mechanism herein shown and described, is admirably adapted to fulfil the objects primarily stated, it is to be understood that it is not intended to confine the invention to the one form of embodiment herein disclosed, for it is susceptible of embodiment in various forms all

coming within the scope of the claims which follow.

What is claimed is:—

1. In a machine of the class described, the combination with a plurality of printing devices, of a differentially movable element, means carried by said differentially movable element for controlling the printing devices in desired combinations, and means for differentially operating the movable element. 65
2. In a machine of the class described, the combination with a plurality of printing devices, of a differentially rotatable element, means carried by said differentially rotatable element for controlling the printing devices in desired combinations, and means for differentially rotating said rotatable element. 70
3. In a machine of the class described, the combination with a plurality of printing devices, of a differentially rotatable shaft, a plurality of elements carried by said shaft arranged to control the operations of the printing devices in various combinations, and means for differentially rotating the shaft. 75
4. In a machine of the class described, the combination with a plurality of printing devices, of a differentially movable element, means carried by said differentially movable element for controlling the printing devices in desired combinations, and means for controlling the movement of the differentially movable element. 80
5. In a machine of the class described, the combination with a plurality of printing devices, of a differentially movable element, means carried by said differentially movable element for controlling the printing devices in desired combinations, and manipulative means for controlling the movement of the differentially movable element. 85
6. In a machine of the class described, the combination with a plurality of printing devices, of a differentially movable element, means carried by said differentially movable element for controlling the printing devices in desired combinations, and manipulative means for differentially operating the movable element. 90
7. In a machine of the class described, the combination with a plurality of printing devices, of a differentially rotatable element, means carried by said differentially rotatable element for controlling the printing devices in desired combinations, and manipulative means for differentially rotating said rotatable element. 95
8. In a machine of the class described, the combination with a plurality of printing devices, of a differentially rotatable shaft, a plurality of elements carried by said shaft arranged to control the operations of the printing devices in various combinations, and manipulative means for differentially positioning the movable element 100 to determine the printing devices to be operated during operation of the operating mechanism. 105
9. In a machine of the class described, the combination with a plurality of printing devices, of an operating mechanism common thereto, a differentially movable element, means carried by the differentially movable element for controlling the printing devices in desired combinations, and means for differentially positioning the movable element 110 to determine the printing devices to be operated during operation of the operating mechanism. 115
10. In a machine of the class described, the combination with a plurality of printing devices, of an operating mechanism common thereto, a differentially movable element, means carried by the differentially movable element for controlling the printing devices in desired combinations, and manipulative means for differentially positioning the movable element as a preliminary to an operation of the operating mechanism whereby to predetermine the printing devices to be operated at an operation 120 of said mechanism. 125
11. In a machine of the class described, the combination with a plurality of printing devices, of a differentially movable element, a series of controlling devices carried by said movable element, means for imparting differential movement to the movable element, and connections operated by the controlling devices for rendering the printing devices effective in desired combinations. 130
12. In a machine of the class described, the combination with a plurality of printing devices, of a differentially rotatable shaft, a series of controlling devices carried by the shaft, means for differentially rotating said shaft, and connections operated by the controlling devices for rendering the printing devices effective in predetermined combinations. 135
13. In a machine of the class described, the combination with a printing mechanism comprising check indorsing, check issuing, amount printing, checking strip and permanent record strip devices, of a differentially movable element, means carried by said movable element for controlling said devices in predetermined combinations, and means for imparting differential movement to the movable element whereby to position the controlling devices. 140
14. In a machine of the class described, the combination with a printing mechanism comprising check indorsing, check issuing, amount printing, checking strip and permanent record strip devices, of a differentially rotatable element, means carried by said element for controlling the effectivity of desired combinations of said devices, and 145

means for differentially rotating the rotatable element to position said controlling means.

15. In a machine of the class described, 5 the combination with a plurality of totalizers, of actuators therefor, manipulative means for selecting the totalizers for actuation, a plurality of printing devices, and means controlled by the aforesaid manipulative means for rendering said devices effective in various desired combinations.

16. In a machine of the class described, 15 the combination with a plurality of totalizers, of actuators therefor, manipulative means for selecting the totalizers for actuation, a printing mechanism comprising check indorsing, check issuing, amount printing, checking strip and permanent record strip devices, and means controlled by 20 the aforesaid manipulative means for rendering said devices effective in various desired combinations.

17. In a machine of the class described, 25 the combination with a movable frame, of a plurality of totalizers carried by said frame and arranged to receive entries of different classes, a set of actuators common to the totalizers, manipulative means for moving the movable frame to establish co-operative relation between any desired totalizer and the actuator, printing mechanism comprising check indorsing, check issuing, check printing, checking strip and permanent record strip devices, and means 30 controlled by the aforesaid manipulative means for rendering different combinations of said devices effective according to the various classes of transactions entered in the totalizers.

40 18. In a machine of the class described, 40 the combination with a rotatable frame, of a plurality of totalizers carried by said frame, a set of actuators common to the totalizers, manipulative means for rotating the carrying frame to bring any desired totalizer into co-operative relation with the actuators, printing mechanism comprising check indorsing, check issuing, check printing, checking strip and record strip devices, 45 and means rotated by the manipulative means for controlling the effectivity of said devices in predetermined combinations.

19. In a machine of the class described, 55 the combinations with a plurality of totalizers, of actuators therefor, an adjustable lever and connections operated thereby for establishing co-operative relation between the actuators and any desired totalizers, a printing mechanism comprising check indorsing, check issuing, check printing, checking strip and record strip devices, and means whereby adjustments of the aforesaid lever will render said devices effective in predetermined combinations.

20. In a machine of the class described, 65 the combination with a driving element, of a printing device driven by the driving element and adjustable to different positions with reference to said element, and devices forming a permanent driving connection 70 between the driving element and the printing device arranged to permit the aforementioned adjustment of the printing device without disabling the driving connection. 75

21. In a machine of the class described, 80 the combination with a driving gear, of a printing device adjustable to different positions with reference to the driving gear and comprising a driven gear, and gearing forming a driving connection between the driving gear and the driven gear arranged to permit the aforementioned adjustment of the printing device without disabling the driving connection. 85

22. In a machine of the class described, 90 the combination with a printing device adjustable to a plurality of positions and comprising a driven gear, of a driving gear having a fixed axis, and a plurality of gears 95 forming a driving connection between the driven gear and the driving gear and having axes movable as an incident to adjustment of the printing device whereby to permit said adjustment without disabling the driving connection.

23. In a machine of the class described, 100 the combination with type carriers and means for taking impressions therefrom, of a printing device movable bodily to different positions with reference to the type carriers and comprising a driven gear, a driving gear having a fixed axis, and gearing forming a permanent driving connection between the driving gear and the driven gear arranged to permit the aforementioned adjustment of the printing device without disabling the driving connection. 105

24. In a machine of the class described, 110 the combination with a device for printing on record material, adjustable to different positions with reference to the record material and comprising a driven gear, a driving gear having a fixed axis, and a plurality 115 of gears forming a permanent driving connection between the driving gear and the driven gear and provided with movable axes whereby to permit the aforementioned adjustment of the printing device without disabling said driving connection. 120

25. In a machine of the class described, 125 the combination with a printing device comprising a driven gear and adjustable bodily to print at desired points on a record sheet, of a driving gear having a fixed axis, a plurality of links intermediate the driving gear and the driven gear, a plurality of gears rotatably mounted on said links and forming

a driving connection between the driving gear and the driven gear, the links being arranged to permit the aforementioned adjustment of the printing device without dis-
5 abling the driving connection between the driving gear and the driven gear.

26. In a machine of the class described, the combination with a rotatable element, of devices having an invariable extent of movement for rotating said element, and an adjustable screw positioned to render said devices ineffective during a part of their movement.

27. In a machine of the class described, the combination with a record strip storage roll, of devices for driving the roll whereby to space the record strip, and a set screw positioned to render said driving devices ineffective during a part of their movement.

28. In a machine of the class described, the combination with a record strip storage roll comprising a ratchet disk, of an element having an invariable extent of movement, a pawl carried by said element and arranged to drive the ratchet disk to space the record strip, and a set screw arranged to disconnect said pawl and ratchet disk during a part of the movement of the pawl carrying element.

29. In a machine of the class described, the combination with a record strip storage roll, of devices having an invariable extent of movement for driving the roll whereby to space the record strip, and a screw adjustable to disable the driving devices at desired points in their movement whereby to regulate the width of the spaces on the record strip.

30. In a machine of the class described, the combination with a record strip storage roll, of an element having a reciprocation of invariable extent, a pawl carried by said element for rotating the storage roll whereby to space the record strip, and a screw adjustable to disable the driving pawl at desired points in the reciprocation of the aforesaid element whereby to regulate the width of the spaces on the record strip.

31. In a machine of the class described, the combination with a set of type carriers, of a plurality of record strip devices, an invariably moved element, and manipulatively operated devices for rendering the invariably moved element effective to establish coöperative relationship between the type carriers and the desired record strip device and maintain said relationship during successive operations without intervening manipulations of the manipulative devices.

32. In a machine of the class described, the combination with type carriers, of an adjustable frame, a plurality of record strips carried by the frame, an invariably moved element, manipulative devices, and connec-

tions operated by the invariably moved elements under control of the manipulative devices for adjusting the aforesaid frame to establish coöperative relationship between the type carriers and the desired record strip, said frame remaining in any adjusted position during successive operations without intervening manipulations of the manipulative devices.

33. In a machine of the class described, the combination with type carriers, of an adjustable frame, a plurality of record strips carried by the frame, an element connected to the frame and operable to adjust same with reference to the type carriers, a member having an invariable movement, manipulative devices, and means controlled by the manipulative devices for rendering the invariably moved member effective to operate the connected element in either direction whereby to adjust the frame and establish coöperative relationship between the type carriers and the desired record strip, the frame remaining in any adjusted position during successive operations without intervening operations of the manipulative devices.

34. In a machine of the class described, the combination with type carriers, of a sliding frame, a plurality of rock frames pivoted to the sliding frame, a pivoted element operatively connected to said sliding frame, an invariably moved member, manipulative devices, means controlled by the manipulative devices for causing the invariably moved element to engage the pivoted element at either side of its pivot whereby to slide the sliding frame and position the desired rock frame in coöperative relationship to the type carriers, and invariably moved means for rocking the positioned frame.

35. In a machine of the class described, the combination with type carriers, of a sliding frame, a plurality of rock frames pivoted to the sliding frame, a pivoted element operatively connected to said sliding frame, an invariably moved member, manipulative devices, and means controlled by the manipulative devices for causing the invariably moved element to engage the pivoted element at either side of its pivot whereby to slide the sliding frame and position the desired rock frame in coöperative relationship to the type carriers.

36. In a machine of the class described, the combination with a plurality of printing devices, of manipulative devices common to the printing devices, and means controlled by the manipulative devices for rendering the printing devices effective in various desired combinations.

37. In a machine of the class described, the combination with a plurality of printing devices, of an adjustable lever, and means

controlled by said lever for rendering the printing devices effective in various desired combinations.

38. In a machine of the class described, 5 the combination with a driving element, of an accounting device driven by said element and adjustable to different positions with reference to the driving element, and means forming a permanent driving connection be- 10 tween the driving element and the accounting device arranged to permit the aforementioned adjustment of the accounting device without disabling the driving connection.
- 15 39. In a machine of the class described, the combination with a driving gear, of an accounting device adjustable to different positions with reference to the driving gear and comprising a driven gear, and gearing 20 forming a driving connection between the driving gear and the driven gear arranged to permit the aforementioned adjustment without disabling the driving connection.
- 25 40. In a machine of the class described, the combination with a driving gear having a fixed axis, of an accounting device adjustable to different positions with reference to said axis and comprising a driven gear, and a plurality of gears forming a permanent 30 driving connection between the driving gear

and having movable axes whereby to permit the aforementioned adjustment without disabling said driving connection.

41. In a machine of the class described, the combination with a plurality of printing 35 devices, of devices for operating said devices in various predetermined combinations, manipulative means, and connections whereby any desired combination of printing devices may be selected for operation by 40 a single operation of the manipulative means.

42. In a machine of the class described, the combination with a plurality of printing 45 devices operable in various predetermined combinations, of a plurality of totalizers, there being a totalizer for each combination of printing devices, and manipulative means common to the printing devices and totalizers whereby any desired combination 50 of printing devices and the corresponding totalizer may be simultaneously selected for operation by a single operation of the manipulative means.

In testimony whereof I affix my signature 55 in the presence of two witnesses.

EDWARD J. VON PEIN.
